UNITED STATES PATENT OFFICE

CHARLES VAN BRUNT, OF SCHENECTADY, NEW YORK, ASSIGNOR TO GENERAL ELECTRIC COMPANY, A CORPORATION OF NEW YORK.

REDUCTION-FURNACE.

No. 903,922.

Specification of Letters Patent. Patented Nov. 17, 1908.

Application filed February 10, 1908. Serial No. 415,025.

To all whom it may concern:

Be it known that I, CHARLES VAN BRUNT, a citizen of the United States, residing at Schenectady, county of Schenectady, State of New York, have invented certain new and useful Improvements in Reduction-Furnaces, of which the following is a specification.

My invention comprises a special reduction furnace for the reduction of metallic compounds, such as oxids, to yield reduced metals of great purity and fineness.

For some purposes it is necessary to obtain a metal in a very fine state of division which at the same time will be exceedingly pure. In order to fulfil both these conditions the metal should be reduced from its compounds in this finely divided condition as subsequent grinding may be impossible, or impracticable because of the danger of introducing impurities. It is well known that finely divided metals are oxidized with great ease, therefore, unusual difficulties present themselves in the reduction of the metal in this condition. For example, the reduction of tungstic oxid with hydrogen takes place according to the following reaction:

This reaction is reversible,—therefore, great care must be used not to bring the reduced tungsten in contact with the watery vapor, which is the by-product of the reaction.

My device is designed to produce a very pure, finely divided tungsten. I accomplish this by effecting a reduction of the oxid in a current of reducing gas, such as hydrogen. The watery vapor, which results from the reaction, is swept by the moving stream of hydrogen, away from the already reduced tungsten. The linear speed of this moving stream of hydrogen must be great enough to carry away the moisture at a rate which will exceed the rate of diffusion of the watery vapor in the opposite direction. In this way I avoid all re-oxidation of the reduced metallic tungsten.

As will be hereinafter described, a number of reduction chambers are connected in series, but between every two consecutive is connected a drying chamber so as to keep the concentration of the watery vapor at a low value. As only a portion of the hydrogen is oxidized in the reaction, the unused hydrogen, together with such additions as necessary to make up the losses, is returned to the furnace.

The various features of novelty of my invention are pointed out in the appended claims; but a better understanding of my invention may be obtained from the following description taken in connection with the accompanying drawings.

Figure 1 shows a perspective view of my reducing furnace, together with a diagrammatic representation of the system for maintaining a continuous circulation of the hydrogen. Fig. 2 shows a longitudinal section of one of the tubular reducing chambers, and also shows a drying chamber. Fig. 3 shows a cross section of the reducing tube taken on line 3—3 of Fig. 2.

As shown in Fig. 1, there are arranged in the upper part of my furnace a number of parallel reduction tubes 1, supported by the framework 2. On the lower part of the furnace are arranged similarly a series of parallel absorbing chambers 3, similarly supported by the framework 2. The reduction chambers are connected in series with the drying chambers by means of tubes 4 in such a manner that gas entering a reduction tube will be carried to a drying tube, then back to a second reduction tube, then to another drying tube, and so on through the furnace. The reduction tubes and connecting tube 4 may be made of any suitable metal, such as copper or iron. The drying tubes 3 may be conveniently made of glass. They may contain any suitable drying agent, as sulfuric acid. The ends of the tubular reduction chambers are water-cooled, as shown in the drawing. As here shown, the water enters by means of a tube 5, and after circulating through the hollow supporting frame 2 is carried away by the tube 6. The cooling arrangement is similar on both sides of the furnace.

The tubular reduction chambers are heated by means of a traveling member 7, which travels from one end of the furnace to the other. The traveling heater 7 is provided with a number of burners. These burners are supplied with gas and air by means of tubes 8 and 9. The traveling heater is moved very slowly along the length of the tubes by means of the worm gear 10, which is driven in any convenient way, such as by chain drive 11. The traveling heater may

be returned at the end of the run to its initial position by disengaging it by hand from the worm gear. This may be accomplished by 5 pressing the spring 12, which will separate the member 13 engaging with the worm gear, and the traveling heater may then be rolled back to its original position.

The furnace is supplied with a reducing gas, as hydrogen, from the reservoir 14, 10 which may be, for convenience, a rubber bag. It is carried by means of the tube 15 through the wash bottle 16, which may be partly filled with a washing liquid, as sulfuric acid, and is carried from thence to the first reduction tube of the furnace. As before described, the gas passes through the furnace, going alternately through a reduction tube and a drying tube, where the products of the reaction are absorbed, and finally 15 passes out in tube 17, is passed through another wash bottle 18, and is returned to the collecting reservoir 14 by means of a pump 19. The hydrogen used up in the reaction is replaced by an additional supply of 20 hydrogen from the reservoir 20, which is supplied from the hydrogen generator. The pressure of hydrogen in the collecting reservoir 14 is at all times indicated by a mercury gage 21.

30 In order to make the zone of heating in the reduction tubes as uniform as possible, the heat is reflected downward by means of the V shaped heat-reflecting shield 22, which may be made of iron lined on its inner 35 surface with some refractory non-conductor of heat, such as asbestos. This heat reflector 22 is connected rigidly to the traveling heater, and, therefore, moves with it across the furnace.

40 Having described my apparatus, I will proceed to explain the operation of the furnace.

The reducible oxid, as, for example, precipitated tungstic oxid WO_3 , of a fineness 45 commensurate with the degree of fineness desired in the reduced metal, is placed in shallow boats, 23, such as shown in Figs. 2 and 3. These boats may be made of copper. The boats partially filled with oxid, are inserted in the reduction tubes 1 of the furnace. The reduction tubes and the drying tubes are then connected in series as before 50 described, but leaving disconnected the return tube 17 where it joins the wash bottle 18. The furnace is connected to the hydrogen supply system, and the flow of hydrogen is started by setting in operation the pump 19. After all the air has been swept out the furnace connection is made between the tube 55 17 and the wash bottle 18, thus permitting a continuous circulation of the hydrogen through the system. The flames in the movable heater 7, in its initial position at the extreme end of the furnace, are lighted, and 60 the chain drive 11 is set into motion. The

movable heater travels across the furnace at a very slow rate of speed, so as to complete the run in about one and one-half hours. The gas flame is so regulated as to produce a temperature in the charge of about 600° to 70 800° C. When the run is completed the gas supply is cut off, the reflector 22 is removed from the tubes. As shown in the drawing, it consists of two identical parts rigidly connected together, so as to balance one another. 75 As here shown, the parts may be simply interchangeable. The hydrogen current is continued in circulation for about ten to twenty minutes, or until the furnace is partly cooled off. The hydrogen supply is then cut off, 80 and the reduction tubes 1 are opened by removing the stoppers 24, and the hydrogen allowed to slowly diffuse. The previous cooling of the furnace and the slow diffusion of the hydrogen are necessary, as the reduced tungsten is very apt to catch fire in the air if this precaution is not taken. The reduced metallic tungsten is now ready to be removed from the furnace.

When a very fine grade of tungsten is 90 made it is sometimes necessary to empty the reduction tubes in an atmosphere of carbon dioxide so as to avoid all possibility of re-oxidation of the tungsten.

I do not desire to limit myself to the 95 particular construction and arrangement of parts here shown, but aim in the appended claims to cover all modifications which are within the scope of my invention.

What I claim as new, and desire to secure 100 by Letters Patent of the United States, is,—

1. The combination of a plurality of tubular envelops, means for producing a flow of reducing agent through said envelops, means for heating a zone of said envelops, and automatic means for progressively advancing the zone of heating longitudinally along the said envelops.

2. The combination of a plurality of tubular envelops connected in series, means for 110 producing a flow of reducing agent through said envelops, means for heating a restricted zone of said envelops, and automatic means for progressively advancing the zone of heating longitudinally along the said envelops.

3. The combination of a plurality of tubular envelops connected in series, containers provided with a moisture absorbing agent in an intermediate relation between successive 120 pairs of the tubular envelops, means for heating a restricted zone of said envelops, and automatic means for progressively advancing the zone of heating longitudinally along the tubular envelops.

4. The combination of a plurality of tubular envelops, means for producing a flow of reducing agent through said envelops, means for heating a restricted zone of said envelops, and automatic means for progress- 130

ively advancing the zone of heating longitudinally along the said envelops, and means for deflecting heat downward upon the heated zone.

5. The combination of a plurality of tubular envelops, means for producing a flow of reducing agent through said envelops, means for heating a contracted zone of said envelops, means for cooling the ends of said

envelops, and automatic means for progressively advancing the zone of heating longitudinally along the said envelops.

In witness whereof, I have hereunto set my hand this 8th day of February, 1908.

CHARLES VAN BRUNT.
